UNITED STATES PATENT OFFICE.

WILLIAM ARTHUR BOND, OF LYNNFIELD, MASSACHUSETTS, ASSIGNOR TO UNITED SHOE MACHINERY COMPANY, OF PATERSON, NEW JERSEY, A CORPORATION OF NEW JERSEY.

GRIPPER.

1,032,269.

Specification of Letters Patent.

Patented July 9, 1912.

Application filed January 18, 1909. Serial No. 472,910.

To all whom it may concern:

Be it known that I, WILLIAM A. BOND, a citizen of the United States, residing at Lynnfield, in the county of Essex and Commonwealth of Massachusetts, have invented certain Improvements in Grippers, of which the following description, in connection with the accompanying drawings, is a specification, like reference characters on the drawings indicating like parts in the several figures.

This invention relates to machines for working uppers over lasts and particularly to the grippers mechanism of such machines.

15 The invention is shown as embodied in grippers adapted for use in machines of the type shown in United States Letters Patent No. 584,744, dated June 15, 1897, and has for its object to improve the construction of 20 the grippers therein shown.

One feature of the invention consists in a novel construction of grippers by which a firmer gripping action is obtained and greater durability secured than in grippers 25 as heretofore constructed. To this end, as herein shown, a fixed gripper jaw is arranged in its carrier with an extended upper end face in engagement with a lower end face of the carrier, whereby rocking of said gripper jaw about its connection with the carrier is avoided when pressure is applied to its gripping face for holding and pulling stock. For further increasing the 30 rigidity of the connection between the gripper jaw and its carrier the jaw is preferably pinned or otherwise secured to the carrier at a plurality of points so that the jaw cannot pivot or turn in the carrier. In order to obtain a firmer gripping of the 35 stock by the two gripping jaws and prevent any tendency of the movable gripper jaw to turn laterally said movable jaw is connected to the fixed jaw by parallel links arranged at opposite sides of the jaws.

40 In the type of machine in which the present invention is herein shown as embodied the grippers are first closed and then automatically uplifted to pull the upper. The grippers closing means includes also a yielding element which, after the jaws have engaged the stock, is compressed or put under tension for increasing the force with which the grippers hold the stock. This yielding element also has the function of enabling 45 the grippers to engage firmly stock varying

in thickness because, if the stock is thick, this element yields to allow the actuating mechanism to make its full stroke without breaking the grippers or crushing the stock.

The machine includes other lasting instrumentalities beside the grippers and is also equipped with tack driving mechanism. These parts are operated in time relation with the grippers and it is frequently desirable to run the machine to cause said 60 other lasting devices or the tacking mechanism to perform their functions when no stock is so presented as to be engaged by the grippers.

In accordance with another feature of this 70 invention provision is made for preventing the gripping faces from being forced into wearing engagement with each other when no stock is interposed between them. This avoids straining the gripper jaws by applying stress to them when they are not in use and also prevents their gripping faces, which are usually toothed or corrugated, from becoming worn by contact with each other. By the use of this feature of the invention 80 the gripping faces of the jaws receive little wear and retain their correct shape for a longer time than heretofore.

In the embodiment of the invention shown the shank of the movable gripper jaw and 85 the shank of the rigid gripper jaw are provided with coöperating, and preferably relatively adjustable, stops which limit the approach of the movable gripper jaw and arrest said jaw before it comes into such 90 engagement with the rigid jaw as would wear the gripping faces.

The features of the invention, including certain details of construction and combinations of parts, will be more fully explained 95 in the following description in connection with the drawings and will then be pointed out in the claims.

Figure 1 is a side elevation partly in section showing the gripper jaws closed. Fig. 100 2 is a detail showing the limiting stops when the jaws are open.

The grippers comprise the jaws 2 and 3 carried by their shanks 4 and 5 the latter being a rod extending through the former 105 and upwardly beyond the ball head of the shank 4 by which the grippers as a whole are suspended from a lever 6. The shank 4 is slotted from front to back at its lower end and provided at the upper end of the slot 110

with an extended face 10. The jaw 2 has a body portion shaped to fit snugly in the slot between the walls of the shank and has an extended upper end face 12 adapted to have a broad bearing against the face 10. This extended engagement between the upper end face of jaw 2 and the face 10 of its shank is designed to minimize the tendency of the jaw to turn with relation to its shank when pressure is exerted against its gripping face for holding and pulling the stock. For further insuring against the tendency of the gripper jaw to turn in its shank said parts are rigidly connected at a plurality of points by rivets or clamping bolts 14. This construction forms a very rigid connection between the gripper jaw and its shank and one which is not liable to become loose under the rapidly recurring strains to which the 15 grippers are subjected in the operation of the machine. The coöperating movable gripper jaw 3 is flexibly connected by a link 15 to its shank 5 and is connected to the rigid gripper jaw by parallel links 16 which are arranged at opposite sides of the gripper jaws, whereby they are spaced a considerable distance apart and prevent any swiveling of the movable jaw about a vertical axis.

20 The grippers are normally held open by a spring 20 which, resting upon a collar 22 secured to the shank 4, presses upwardly against a pin 23 extending outwardly from the shank 5. The grippers are closed by depressing the shank 5 against the action of the spring 20 and this movement is effected by a lever 24. The closing lever is provided at its front end with a spring-pressed plunger 25 which rests upon a cap 26 on the upper end of the shank 5 of the grippers and through which force is transmitted from the lever for closing the grippers. The provision of this yielding element in the closing mechanism allows the 25 grippers to engage and hold with approximately the same force stock varying in thickness. In practice it is desirable that the movement of the closing lever be sufficient to cause the spring surrounding the 30 plunger 25 to be compressed during each closing movement. The gripper shank 5 is provided with an adjustable stop 30 for engaging a stop face 32 on the upper end of the shank 4 of the rigid gripper and thereby 35 limiting the downward movement of the shank 5. By this arrangement the movable gripper jaw may be prevented from closing into wearing contact with the rigid gripper jaw so that wear of their gripping faces, 40 which are usually toothed or corrugated, may be prevented. This is desirable as above suggested because the machine is sometimes run without interposing stock between the gripper jaws and if said jaws 45 were allowed to close against each other

they would become worn and mutilated. The engagement of the gripper jaws when no stock is interposed also causes some noise which it is desirable to avoid. The stop 30 can be adjusted on the shank 5 to arrest the 50 closing movement of jaw 3 before it makes actual contact with the jaw 2 if thick stock is being operated upon. If thin stock is being lasted the stop 30 will be set to permit the jaws to close together for firmly 55 crimping the stock into the teeth of their gripping faces but to prevent the jaws being jammed together and battering one another when closed without any stock between them. The cap 26 is made as a cup nut 60 inclosing the top of the shank 5 and screwing down upon the stop 30 to lock the latter in its adjusted position. The provision of the stop for limiting the approach of the jaws reduces the strain on the rigid jaw 2, because it prevents the impact of the moving 65 jaw against its companion when there is no cushioning stock between them. The stop thus assists in preventing the jaw 2 from working loose.

Having explained the nature of this invention and fully described a construction embodying the same in the best form now known to me, I claim as new and desire to secure by Letters Patent of the United States:

1. In a machine of the class described, the combination with gripper jaws and relatively movable operating bars to which the jaws are connected, of mechanism for actuating one of said bars to close the jaws, and coöperating stops on said bars for arresting the closing movement of the jaws immediately before their gripping surfaces come in contact.

2. In a machine of the class described, the combination with gripper jaws and relatively movable operating bars to which the jaws are connected, of mechanism for actuating one of said bars to close the jaws, a stop on the closing bar arranged for contact with the other bar to limit the extent of closing movement of the jaws, and a cup nut threaded on said closing bar and arranged to clamp the stop in adjusted position on said bar.

3. In a machine of the class described, the combination with gripper jaws and relatively movable operating bars to which the grippers are connected, of yielding mechanism for actuating one of said bars to close the gripper jaws, and coöperating, relatively adjustable stops on said bars for limiting the movement in the direction to close the jaws.

4. In a gripper mechanism, a carrier, a swinging jaw, parallel swinging links arranged upon opposite sides of said jaw and pivotally connected to it and to said carrier, actuating means for said jaw operating

through it and said links to apply to the stock both downward and outward pressure, a coöperating jaw having a laterally extended end face abutting against a coöperating face on the carrier, and securing devices by one of which said links are pivoted to the carrier and which are arranged in a triangle to prevent movement of the jaw relatively to the carrier in response both to 10 the outward and the downward pressure of the swinging jaw.

5. In a gripper mechanism, a recessed gripper carrier, a swinging jaw, parallel swinging links arranged upon opposite sides 15 of said jaw and pivotally connected to it and to said carrier, actuating means for said jaw operating through it and said links to apply to the stock both downward and outward pressure, a coöperating gripping jaw mount-

ed in the recess in the carrier and provided with an end face 10 having a laterally extended bearing against a coöperating face 12 on the carrier, and three non-alined securing devices 14, one of which forms the pivotal connection of the links to the carrier and which together fasten the jaw to the carrier with said faces 10 and 12 in mutually abutting relation, all combined and arranged to hold the jaw rigidly upon the carrier against both the outward and the downward pressure of the swinging jaw. 20 25 30

In testimony whereof I have signed my name to this specification in the presence of two subscribing witnesses.

WILLIAM ARTHUR BOND.
